UNITED STATES PATENT OFFICE.

HUBERT SEIDL, OF OBERHAUSEN, GERMANY, ASSIGNOR TO THE BABCOCK & WILCOX COMPANY, OF BAYONNE, NEW JERSEY, A CORPORATION OF NEW JERSEY.

BOILER FURNACE.

Application filed June 23, 1927, Serial No. 200,797, and in Germany March 12, 1926.

This invention relates to a furnace that is especially useful in connection with the burning of powdered coal. The invention will be described in connection with a boiler furnace, but it is to be understood that it is not restricted to this particular use.

The invention will be understood from the description in connection with the accompanying drawings, in which Fig. 1 is a vertical section through a furnace, partly broken away, showing an illustrative embodiment of the invention; and Fig. 2 is a section along the line 2—2 of Fig. 1. In the drawings reference character 5 indicates the walls of a furnace that may be lined in the usual way with material 6, that is highly refractory. The combustion space of the furnace is indicated at 7 below which the ash hoppers 8 are located. The ash hoppers are provided with sloping floors 9 along which the slag and ashes may be withdrawn through doors 10 in the side of the furnace.

Water tubes 12 extend across the furnace, between the combustion space and the ash hoppers, through the walls of the furnace and enter headers 13 and 14 on the outside of the furnace walls. The headers 13 and 14 may be connected to the circulation system of the boiler (not shown) or to any other convenient source of water through connections 15. A valved drain pipe 16 may be provided for the inlet header 13. The tubes 12 are preferably slightly inclined upwardly from the inlet header toward the outlet header, and are so disposed across the furnace that groups of tubes are located in sloping planes, as most clearly shown in Fig. 2, thus forming roof-shaped arrangements. Each row of tubes in a single plane has the spaces between the tubes closed by plates or flanges 18, and spaces are left between certain of the other tubes through which the slag and ashes descend into the ash hoppers. In the illustrative embodiment of the invention, certain of the tubes are located in a lowermost plane, and other tubes are located in higher planes without having two tubes in the same vertical plane. The tubes may be bent near portions thereof that pass through the furnace walls, as best shown in Fig. 1, in an

appropriate manner to procure the arrangement just described.

In the normal operation of the furnace, the spaces between the lowermost tubes 12 are left open for the passage of slag and ash into the ash hoppers. If the doors 10 are opened while the spaces are left open between the tubes, the inrush of cold air will interfere with combustion in the furnace. In order to prevent this interference, slideable dampers 19 are provided to close the spaces between the lowermost tubes 12 when the doors 10 are to be opened. Rods 20 are connected to the dampers 19 and extend through a wall of the furnace, and have their extending ends threaded to accommodate screw hand wheels 21 by which the dampers can be slid back and forth transversely of the tubes to open or close the spaces between them. The edges of the dampers 19 rest upon supports 22 that may be provided with flanges 23 to serve as guides for the dampers.

I claim:

1. In a furnace, water screen tubes extending across the lower portion of said furnace arranged in separate planes each inclined to the horizontal with spaces between some of said tubes and dampers for controlling said spaces.

2. In a furnace, water screen tubes extending across the lower portion of said furnace arranged in separate planes each inclined to the horizontal, with spaces between some of said tubes and dampers operable from the outside of said furnace for controlling said spaces.

3. In a furnace, water screen tubes extending across the lower portion of said furnace arranged in separate planes each inclined to the horizontal, with spaces between some of said tubes and dampers slideable transversely of said tubes for controlling said spaces.

4. In a furnace, a combustion space and an ash hopper, tubes arranged in separate planes each inclined to the horizontal located between said combustion space and ash hopper and means to close permanently the spaces between some of said tubes and means to close the spaces between some of the other tubes at will.

5. In a furnace, a combustion space and

- an ash hopper, tubes arranged in separate planes each inclined to the horizontal located between said combustion space and ash hopper, means to close permanently the spaces between some of said tubes and means to close the spaces between some of the other tubes at will, said last named means comprising dampers movable across said tubes.
- 10 6. In a furnace, a plurality of spaced groups of water tubes extending across the lower portion of said furnace the tubes of each group lying at a plurality of elevations offset from each other, the spaces between 15 the lowermost tubes and those at higher elevations of each group being closed and the spaces between the lowermost tubes in adjacent groups being closed by dampers.
7. In a furnace, a plurality of spaced groups of water tubes extending across the 20 lower portion of said furnace the tubes of each group lying at a plurality of elevations and in different vertical planes, the spaces between the lowermost tubes and those at higher elevations of each group being closed and the spaces between pairs of tubes in the lowermost row of tubes being closed by dampers. 25

HUBERT SEIDL.
